J. R. KINNEY

LIFTING JACK

Filed March 10, 1924

Fig. 1.

*Inventor:
Justus R. Kinney,
by Walter E. Lombard.
Atty.*

UNITED STATES PATENT OFFICE.

JUSTUS R. KINNEY, OF JAMAICA PLAIN, MASSACHUSETTS.

LIFTING JACK.

Application filed March 10, 1924. Serial No. 698,022.

To all whom it may concern:

Be it known that I, JUSTUS R. KINNEY, a citizen of the United States of America, and a resident of Jamaica Plain, in the 5 county of Suffolk, in the State of Massachusetts, have invented certain new and useful Improvements in Lifting Jacks, of which the following is a specification.

This invention relates to lifting jacks and 10 has for its object the production of a device of this character which will be particularly adapted for use in connection with motor vehicles equipped with balloon tires.

The invention consists primarily of a base 15 having a post extending upwardly therefrom at an angle to the bottom of the base and adapted to move into a perpendicular position as the load-supporting member on said post is moved upwardly thereon.

20 The invention consists further in means whereby the actuating nut on said post may be rotated about said post when desired without affecting the movement of the load-supporting member.

25 The invention consists further in means whereby the load-supporting member is prevented from rotating about the axis of said post.

The invention consists further of certain 30 novel features of construction and arrangement of parts which will be understood readily by reference to the description of the drawings and to the claims to be hereinafter given.

35 For the purpose of illustrating the invention, one preferred form thereof is illustrated in the drawings, this form having been found to give satisfactory and reliable results although it is to be understood that

40 the various instrumentalities of which the invention consists can be variously arranged and organized and the invention is not limited to the precise arrangement and organization of these instrumentalities as herein shown and described except as required by 45 the scope of the appended claims.

Of the drawings:

Figure 1 represents a vertical section of a 50 lifting jack embodying the principles of the present invention.

Figure 2 represents a horizontal section of same on line 2, 2, on Fig. 1.

Figure 3 represents a horizontal section of same on line 3, 3, on Fig. 1.

Figure 4 represents a plan of the lower 55 guide block of the load-supporting member, and

Figure 5 represents a vertical section of same on line 5, 5, on Fig. 4.

Similar characters indicate like parts 60 throughout the several figures of the drawings.

In the drawings 10 is a base plate having secured to the upper face thereof a block 11 having a socket 12 therein, said socket being provided with an inclined wall 13 and an oppositely disposed perpendicular wall 14.

The block 11 has a transverse pin 15 extending across the socket 12, this pin 15 extending through a hole 16 in the lower end 70 of the threaded post 17, said hole 16 having a diameter slightly greater than that of the pin 15.

Normally the post 17 rests against the inclined wall 13 thereby assuming an inclined 75 position as indicated in dotted lines at 18 in Fig. 1.

The post 17 has a groove 19 extending lengthwise thereof into which extends the key 20 in the guide block 21.

This guide block 21 has flat sides which contact with the inner faces of the side walls of a carriage 22, which is formed from a bent plate one portion of which forms a lateral extension 23 to support a load indicated in Fig. 1 as the axle A of a motor vehicle.

The walls of the extension 23 are secured together by rivets 24 and the axle A rests upon the upper edge 25 thereof and against 90 the vertical edge 26 of the carriage 22.

The ends of the plate forming the carriage 22 are divided and the upper portions 27 thereof are secured together by rivets 28 while the lower portions 29 overlap and are 95 secured together by rivets 30, these rivets also securing to the carriage 22 an arm 31 extending downwardly and provided with a finger 32 extending toward the post 17.

The guide block 21 is provided with oppositely disposed trunnions 33 positioned in cylindrical openings in the side walls of the carriage 22 and in which they are adapted to oscillate.

A similar guide block 34 is mounted in 105 the same manner at the upper end of the carriage 22 but this block is not provided with a key 20 as is the case with the block 21.

The guide block 21 extends slightly below the lower edge of the carriage 22 and rests upon the nut 35 which is threaded to the post 17.

5 By rotating this nut 35 the carriage 22 may be moved lengthwise of the post 17.

Any means may be employed to impart rotation to the nut 35 but preferably said nut has formed integral therewith a bevel gear 36 the teeth of which mesh with the teeth of a pinion 37 fixedly secured to an actuating shaft 38 having bearings in the arm 31 and the overlapped ends 29 of the plate forming the load-supporting member 22, 23.

10 The finger 32 extends beneath the gear 36 and is spaced therefrom a sufficient distance to permit the load-supporting member 22, 23 being lifted manually until the pinion 37 is disengaged from gear 36.

20 When this has been done the nut 35 may be rotated manually until it is approximately in the position where the extension 23 will engage the load to be lifted.

25 When thus adjusted the load-supporting member 22, 23 is permitted to again rest upon the nut 35, the extension 23 is inserted beneath the axle A, and the latter is lifted by rotating the actuating shaft 38 in any 30 well known manner.

While the nut 35 is free to rotate upon the post 17 the load-supporting member 22, 23 is prevented from rotation by the key 20 in the groove 19.

35 It has been found that best results are obtained in lifting a load by having the post 17, at the start, in the position indicated by the dotted lines 18, that is inclined from a perpendicular away from the load A with 40 the lower end of post 17 resting against the inclined wall 13.

45 As the load A is lifted the weight thereof will gradually move the post 17 about its pivot 15 from its inclined position 18 until it reaches a perpendicular position with its lower end bearing against the vertical wall 14.

50 This makes a very effective lifting jack particularly adapted for use in connection with motor vehicles and is easily operated as the two guide blocks 21, 34 prevent any cramping upon the post 17 while the load A is being lifted.

55 It is very durable and constructed at little cost.

It is believed that the operation and many advantages of the invention will be fully apparent without further description.

Having thus described my invention, I 60 claim—

65 1. In a device of the class described, a threaded post; a base having a socket in which the lower end of said post is pivotally mounted, said socket having one inclined wall and an oppositely disposed perpendicular wall; and a load supporting member movable lengthwise of said post.

lar wall; and a load-supporting member movable lengthwise of said post.

2. In a device of the class described, a threaded post having a groove extending lengthwise thereof; a base therefor; a load-supporting member on said post; a guide member surrounding said post with trunnions in bearings in said load-supporting member; a key in said guide member extending into said groove; and means for moving said load-supporting member lengthwise of said post. 70

3. In a device of the class described, a threaded post having a groove extending lengthwise thereof; a base therefor; a load-supporting member on said post; two guide members surrounding said post with trunnions in bearings in said load-supporting member; a key in one guide member extending into said groove; and means for moving said load-supporting member lengthwise of 80 said post. 85

4. In a device of the class described, a threaded post; a base therefor; a load-supporting member movable lengthwise of said post; a revoluble nut threaded to said post and upon which said member normally rests; and means whereby the load-supporting member may be raised from said nut to permit the latter to be manually adjusted on 90 said post. 95

5. In a device of the class described, a threaded post; a base therefor; a load-supporting member movable lengthwise of said post; a revoluble nut threaded to said post and upon which said member normally rests, 100 said nut having bevel gear teeth on its periphery; a pinion carried by said load-supporting member coacting with said bevel gear teeth; means for rotating said pinion; and means whereby said load-supporting member may be lifted sufficiently to disengage 105 said pinion and gear teeth.

6. In a device of the class described, a threaded post; a base therefor; a load-supporting member movable lengthwise of said post; a revoluble nut threaded to said post and upon which said member normally rests, 110 said nut having bevel gear teeth on its periphery; a pinion carried by said load-supporting member coacting with said bevel gear teeth; means for rotating said pinion; and an arm secured to said load-supporting member having a finger extending beneath 115 said nut and spaced therefrom sufficiently to permit the pinion to be disengaged from said gear teeth.

7. In a device of the class described, a threaded post; a base plate; a block secured thereto and having a socket in which the lower end of said post is pivotally mounted, 120 said socket having one inclined wall and an oppositely disposed perpendicular wall; and a load supporting member movable lengthwise of said post. 125

8. In a device of the class described, a threaded post having a groove extending lengthwise thereof; a base therefor; a load supporting member on said post consisting of a bent plate the ends of which are secured together; a guide member surrounding said post with trunnions in bearings in the side walls of said load-supporting member; a key in said guide member extending into said groove; and means for moving said load-supporting member lengthwise of said post.
- Signed by me at 746 Old South Bldg., Boston, Massachusetts, this 8th day of March, 1924.

JUSTUS R. KINNEY.
